(57) **CLAIM**

I claim the ornamental design for a relaxation sound machine, as shown and described.

DESCRIPTION

FIG. 1 is a frontal perspective view of the present invention.

FIG. 2 is a frontal plan view of the present invention.

FIG. 3 is a rear plan view of the present invention.

FIG. 4 is a top plan view of the present invention.

FIG. 5 is a bottom plan view of the present invention; and, FIG. 6 is a side plan view of the present invention.
